COIN-CONTROLLED MAGAZINE SWITCH
MECHANISM

Fred H. Osborne, and Theodore M. Wright, North Tonawanda, N. Y., assignors to The Rudolph Wurlitzer Company, North Tonawanda, N. Y., a corporation of Ohio

Application December 20, 1937, Serial No. 180,728

6 Claims. (Cl. 200—33)

This invention relates generally to coin-control devices and more particularly to a coin-controlled magazine switch mechanism adapted for use with coin-operated phonographs and other coin-controlled devices or apparatus.

It has for one of its objects to provide a magazine switch mechanism of this character which is so designed and constructed as to be positive and reliable in operation, which is not liable to get out of order, and which is not subject to jamming.

Another object of the invention is the provision of a coin-control device having simple and effective means for governing the closing and opening movements of the controlling switch of the phonograph or like apparatus and which means includes relatively displaceable elements designed for movement in the same direction to produce a divergent or convergent relationship to effect, respectively, the closing of the switch upon the deposit of one or more coins and the opening of the switch when service has been rendered for the last coin deposited.

Other features of the invention reside in the construction and arrangement of parts herein-after described and particularly pointed out in the appended claims.

In the accompanying drawings:

Figure 1 is a fragmentary rear view of the chassis of an automatic phonograph showing our improved coin-control magazine switch mechanism associated therewith. Figure 2 is an enlarged front view of the magazine switch mechanism as operatively connected for electrical or remote control. Figure 3 is a left end view of such mechanism showing the switch-governing elements and associated parts. Figure 4 is a right end view of the same showing the electrically-controlled shaft actuating means. Figure 5 is a vertical section taken on line 5—5, Figure 3. Figure 6 is a perspective view of one form of coin slide mechanism which may be operatively connected with the actuating shaft of our magazine switch assembly. Figure 7 is a fragmentary horizontal section taken in the plane of line 7—7, Figure 3.

Similar characters of reference indicate corresponding parts throughout the several views.

While our magazine switch mechanism has been designed more particularly for use and has been shown in conjunction with coin-operated phonographs, it is to be understood that it is likewise applicable to other coin-controlled instruments or apparatus, and in its use it may be initiated electrically by remote control in substan-

tially the manner shown in Figures 1, 2 and 4, or it may be initiated mechanically at the instrument through the medium of a coin slide mechanism, such, for example, as depicted in Figure 6.

In its general organization, the magazine switch assembly includes a switch included in the motor or other operating circuit of the phonograph or like apparatus; relatively movable switch-governing elements which are adapted, when engaged, to effect the opening of the motor circuit and which are adapted, firstly, to be actuated in a relative direction to become separated or disengaged to effect the closing of such circuit and maintain it closed for a predetermined time period, as determined by the number of coins or coin value deposited, and, secondly, to be actuated in a like relative direction to approach or converge toward each other in ultimate engagement to effect the opening of the motor circuit; coin-controlled means for controlling the separating or divergent movement of the switch-governing elements; and means operated from the phonograph, say, after a record has been played, for controlling the approaching or convergent movement of such elements to automatically open the circuit and stop the phonograph when the last record for the number of coins deposited has been played.

By way of example, our magazine switch assembly is shown in connection with an automatic or multi-selective type of phonograph, the numeral 10 indicating the chassis generally, 11 the supporting frame of the magazine switch mechanism which is appropriately mounted on the chassis or cabinet of the phonograph, and 12 a coin chute containing electrical contacts adapted to be closed by an inserted coin for in turn actuating the magazine switch mechanism. Such type of coin chute may be used in the remote control of a phonograph, whereas in Figure 6 we show a coin slide mechanism which is usually applied directly to the phonograph and which is operatively connected to the magazine switch mechanism for actuating it.

The working parts of the magazine switch mechanism are mounted as a unitary assembly on the supporting frame 11, 13 indicating the actuating shaft of the mechanism which is journaled at its ends in said frame and which shaft is adapted to be actuated by the electrical coin-control mechanism shown in Figures 1, 2 and 4 and generally indicated by the numeral 14, or by the coin slide mechanism shown in Figure 6 and indicated generally by the numeral 15, the actuation of this shaft, in either case, controlling the

closing of a pair of switch-governing elements 16, 17 which in turn control an actuatable arm or part 18 of a micro or like switch 19 included in the operating circuit of the phonograph or other apparatus. In this instance, the switch includes a fixed contact 20 and a spring-pressed movable contact or button 21 actuated in response to the opening and closing movements of the controlling arm 18, these contacts being connected to the operating circuit, such as the motor 22 of the phonograph.

The switch-governing elements 16 and 17 are disposed in adjoining cooperative relation at one end of the shaft 13, the element 16 being substantially in the form of an arm which is fixed as indicated at 23 on the shaft so as to turn therewith when motion is imparted thereto, while the companion switch-governing element 17 is laterally displaceable into and out of bearing engagement with the former and is likewise disposed radially of the shaft but loosely mounted thereon for independent relative movement about its axis. By preference, the switch-governing element 17 is borne by and pivoted at 24 to the inner face of a ratchet wheel 25 which is loosely mounted on the shaft 13 between the elements 16 and 17 in the manner shown in Figures 2 and 5. This switch-governing element 17 is shaped to freely straddle or embrace the shaft or the hub of the ratchet wheel and is free to be displaced about its pivot in a direction axially of the shaft or toward and from the face of the ratchet wheel. The intermediate portion 26 of the element 17 is adapted, through the medium of an interposed washer 27, to abut against the upper or free end of the switch-actuating arm 18, whereby, when the element 17 is displaced in a direction away from the ratchet wheel, as seen by dotted lines in Figure 5, it serves to open the switch 19, and when shifted in the opposite direction to the full line position seen in the same figure, the switch is automatically closed. As shown in Figure 5, the spring-pressed switch contact 21 tends constantly to seek a closed position, and this also tends to rock the arm 18 and switch-governing element 17 to the full line position shown in such figure. At its upper or free end the switch-governing element 17 is provided with an outwardly-facing lug or projection 28 which passes freely through an opening 29 in the ratchet wheel 25 for cooperating engagement with the opposing face of the companion switch-governing element 16. As seen in Figure 7, the contacting end of the lug 28 is beveled as indicated at 30, so that during a movement of the switch-governing element 17 relative to the companion element 16, the beveled end of the lug 30 will ride beneath the opposing face of said element 16 and effect an inward displacement of the element 17 to the dotted line, switch-opening position shown in Figure 5. Likewise, when the shaft-attached element 16 moves relative to the companion element 17, as when effecting a closing of the switch 19, such element 17 will be gradually displaced toward the face of the ratchet wheel 25 by the tension on the switch-actuating arm 18 to switch-closing position.

When a coin is deposited in either the electrical type or coin slide type of coin mechanism heretofore referred to, the shaft 13 is revolved in a counter-clockwise direction, viewing Figure 3, a predetermined distance for each unit coin deposited, and in so doing the element 16 fixed on the shaft is angularly displaced from the companion element 17 to effect a closing of the switch

18. With each unit coin deposited, the element 16 diverges a greater distance from the then stationary switch-governing element 17. Referring to the electrical coin-control mechanism shown in Figures 1, 2 and 4 for actuating the shaft 13, the numeral 31 indicates a ratchet wheel fixed on the other end of the shaft 13 which is adapted to be actuated by the plunger 32 of a solenoid 33, included in the coin control circuit 34, through the medium of a spring-pressed pawl 35 mounted on a rock lever 36 pivoted on the shaft and having one arm connected at one end to the solenoid-plunger. A spring 37 is connected to the other lever-arm for urging the same and the parts connected thereto to their initial position after the coin circuit is opened. Also cooperating with the ratchet wheel 31 is a weighted escapement pawl 31a which constitutes a forward and backward stop therefor. Thus, whenever a coin is deposited in the chute 12, the circuit of the solenoid 33 is closed, the plunger 32 is pulled inwardly and the ratchet wheel 31, together with the shaft 13, is moved a distance of one tooth. This same movement is transmitted to the switch-governing element 16 fixed on the opposite end of the shaft and results in such element riding off the lug 28 of the companion switch-governing element 17 to effect the automatic closing of the switch 19 and start the phonograph in operation. Should more than one coin be deposited, the shaft 13 will be moved a distance of one tooth for each coin so deposited which will result in the element 16 being displaced farther from and in a more or less divergent relation to the companion element 17 to thereby keep or maintain the switch 19 closed for the predetermined time period required for insuring the patron the value received for the coins deposited.

After each unit coin is registered in the magazine switch mechanism in the manner above set forth, there are means provided which function to restore such mechanism to switch-opening position when the patron has received the value received for the coin deposited. In the case of any automatic phonograph, such restoration is effected in step by step fashion at the end of play of each record selection and during such period motion is transmitted to the ratchet wheel 25 to bring the switch-governing element 17 toward the companion element 16 and ultimately in engaging relation therewith to effect the opening of the operating circuit of the phonograph. To this end, a pawl 38 is disposed in cooperating relation with the toothed periphery of the ratchet wheel 25, this pawl being guided on a suitable bracket 39 attached to the frame 11 and yieldably attached at its lower end to one arm of a bell crank lever 40 pivoted at 41 and having its other arm connected by a link 42 to an actuatable part, say, 43 of the phonograph, such part in this instance constituting an element of the record changing mechanism and being moved in a direction at the end of playing a record to rock the bell crank in a direction to move the pawl 38 upwardly and advance the ratchet wheel 25 a distance of one tooth in a counter-clockwise direction, that is, in the same direction in which the shaft 13 is actuated by the coin control units 14 or 15. If desired, a pawl 44 having a roller or like element 45 thereon may be provided for operative engagement with the ratchet wheel 25 to constitute a forward and backward stop for the ratchet wheel. It will thus be seen that when each record is played, the pawl 38 is actuated to advance the ratchet wheel one tooth to thereby

bring the switch-governing element 17 nearer the companion element 16, and when the last record for the coin value deposited has been played, such element 17 will have reached a position in register or alignment with that of the companion element 16 to effect the opening of the switch 18 in the manner heretofore described.

In Figure 6 we have shown, by way of example, a coin slide mechanism which may be employed for initiating the mechanical actuation of the shaft 13. This coin slide unit includes a plurality of coin slides 46 for receiving coins of different denominations, say 5, 10 and 25 cent pieces, and each of these slides is adapted to govern and control the movement of a ratchet and pawl mechanism indicated generally at 47 for imparting a predetermined degree of rotation to the shaft in accordance with the coin value deposited. The nickel slide imparts a one tooth movement to its companion ratchet mechanism 47 to turn the shaft 13 and switch-governing element 16 a like distance, while the dime and quarter slides impart a two-tooth and five-tooth movement, respectively, to their companion ratchet mechanisms and thence to said shaft 13.

While manifestly simple and compact in construction, this improved coin-control magazine switch mechanism is so designed that jamming of its parts is eliminated, it having been noted that the switch-governing elements 16 and 17, when moved relatively to each other to assume more or less variable angular positions, travel in the same direction when seeking a switch-closing or switch-opening position.

We claim as our invention:

1. A switch-controlling device, comprising a shaft adapted to be rotated in step by step fashion in one direction, relatively movable switch-governing elements mounted on said shaft, one of said elements being fixed on said shaft for movement therewith in a direction away from the companion element to close the switch, a ratchet wheel loosely mounted on said shaft in juxtaposition to said elements, the other of said elements being pivoted to said wheel for displacement to and from a switch-closing position and having a part disposed for engagement with and in the turning path of the companion element for governing such position, said elements when engaged maintaining the switch in open position and when disengaged effecting the closing of the switch, and means engageable with said ratchet wheel for turning it in a direction to bring its switch-governing element in a direction toward the companion element to open the switch.

2. A switch control mechanism, comprising a switch, a shaft, relatively movable switch-governing elements disposed substantially radially of said shaft, for interengagement at a predetermined time in their relative movements to open the switch and for disengagement at other times to close the switch, one of said elements being fixed thereon to turn therewith, a rotatable member loosely mounted on said shaft and to which the other element is pivoted for lateral displacement by the companion element into and out of switch-closing position, means for actuating said shaft and its fixed switch-governing element in a direction to control the relative movement of said switch-governing elements out of operative engagement to close the switch, and means for actuating the rotatable member of said displaceable switch-governing element in a

like direction to control the relative movement of such elements into operative engagement to open said switch.

3. A switch control mechanism, comprising a rotatable member, a switch-governing element pivoted thereon and movable to and from a switch-closing position, a shaft constituting a support for said rotatable member and having an arm fixed thereon and disposed for operative engaging relation with said switch-governing element for moving the latter to switch-opening position, means for actuating said shaft in a direction to move its arm from engaging relation with said element to permit the latter to assume a switch-closing position, and means for moving the rotatable member of said switch-governing element in the direction of movement of said shaft to present such element into operative switch-opening engagement with said shaft-arm.

4. A switch control mechanism, comprising a switch-governing element movable to and from a switch-closing position, a shaft having an arm fixed thereon and disposed for operative engaging relation with said switch-governing element for moving the latter to switch-opening position, means for actuating said shaft in a direction to move its arm from engaging relation with said element to permit the latter to assume a switch-closing position, a ratchet wheel loosely mounted on said shaft between said arm and said switch-governing element and constituting a support for the latter, said switch-governing element being pivoted to the face of the ratchet wheel to rock toward and from the same to and from its switch-closing position, and means for actuating said ratchet wheel in the direction of movement of said shaft toward switch-opening relation to said shaft-arm.

5. A switch control mechanism including a part to be actuated for opening and closing the switch, a shaft having an arm radially fixed thereon, a ratchet wheel loosely mounted on said shaft with one face thereof alongside said arm for rotation independently thereof, said wheel having an opening therein, a lever pivoted on the opposite face of said ratchet wheel axially of said shaft for lateral displacement toward and from such face and in cooperative engagement with the actuatable part of said switch for controlling the same, said lever having a projection thereon extending through said wheel-opening for engagement with said shaft-arm in switch-opening position, means for actuating said shaft in one direction to effect a divergent angular displacement of its arm from said pivoted lever to cause a closing of the switch, and means for moving said ratchet wheel in a like direction to effect a convergent displacement of its lever toward and in switch-opening engagement with said arm.

6. A switch control mechanism, comprising a switch, a shaft, a ratchet wheel loosely mounted thereon, relatively movable switch-governing elements disposed for operative engagement at a predetermined time in their relative movements to open the switch and for disengagement at other times to close the switch, said elements being arranged substantially radially of said shaft at opposite sides of said wheel, one of said elements being fixed on said shaft and the other being pivotally mounted on said wheel and laterally displaceable by and relative to its companion element into and out of switch-closing position, means for actuating said shaft and

- its fixed switch-governing element in a direction to control the relative movement of said switch-governing elements to close the switch, said means including a second ratchet wheel fixed on
5 said shaft and means for actuating said ratchet wheel predetermined distances, and means engageable with said first-named ratchet wheel for actuating said displaceable switch-governing element in a like direction to control the relative movement of such elements to open the switch.
